US00D584765S

(12) **United States Design Patent**
Park et al.

(10) **Patent No.:** US D584,765 S
(45) **Date of Patent:** ** Jan. 13, 2009

(54) **DEVELOPMENT DEVICE FOR LASER
PRINTER**

(75) Inventors: **Gyeong-Sun Park**, Seoul (KR); **Yun-Gi Hong**, Kyunggi-do (KR); **Bong-Uk Lim**, Kyunggi-do (KR)

(73) Assignee: **Samsung Electronics Co., Ltd.**, Suwon, Kyunggi-Do (KR)

(**) Term: **14 Years**

(21) Appl. No.: **29/292,077**

(22) Filed: **Sep. 27, 2007**

(51) **LOC (9) Cl.** 16-03

(52) **U.S. Cl.** D18/43

(58) **Field of Classification Search** D14/471; D18/12, 36-40, 43, 44, 46-49, 56; 222/DIG. 1; 347/197, 222; 399/24-28, 107-112, 119, 399/121, 122, 222-224

(57) **CLAIM**

The ornamental design for a development device for laser printer, as shown and described.

DESCRIPTION

FIG. 1 is a top front perspective view of a development device for laser printer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict environmental subject matter only and form no part of the claimed design.
